(No Model.)

J. W. FOX.
LOCOMOTIVE ASH PAN.

No. 549,120.

Patented Nov. 5, 1895.

Fig. 1.

UNITED STATES PATENT OFFICE.

JOHN W. FOX, OF CHANUTE, KANSAS, ASSIGNOR OF ONE-HALF TO JOHN W. EATON, OF SAME PLACE.

LOCOMOTIVE ASH-PAN.

SPECIFICATION forming part of Letters Patent No. 549,120, dated November 5, 1895.

Application filed June 29, 1895. Serial No. 554,469. (No model.)

To all whom it may concern:

Be it known that I, JOHN W. FOX, a citizen of the United States, residing at Chanute, in the county of Neosho and State Kansas, have 5 invented a new and useful Locomotive Ash-Pan, of which the following is a specification.

This invention relates to improvements in locomotive ash-pans which are adapted to be cleared of the ashes without requiring the fireman to get beneath the engine or the stopping of the latter to dump the ashes and cinders.

The object of the invention is to scrape the sliding cut-off at the bottom of the ash-pan and to obviate the lodgment of ashes and cinders between the said cut-off and its guides.

Other objects will become apparent as the invention is disclosed and understood, and to this end the improvement consists of novel features which hereinafter will be more fully 20 described and claimed.

In the accompanying drawings, Figure 1 is a perspective view of a locomotive ash-pan embodying the essence of the present invention, the cut-off being partially withdrawn. Fig. 2 25 is a vertical longitudinal section thereof. Fig. 3 is a cross-section of the same. Fig. 4 is a detail view in section, on an enlarged scale, of the edge portion of the cut-off and the guide therefor.

30 The ash-pan, which may be of usual form, has outwardly-extending flanges 1 along the upper edges of its sides 2 to receive the fastenings by means of which the said pan is secured to the framework of the engine. The bottom 3 is formed with a series of discharge-openings 4 at intervals in its length, and these discharge-openings extend the entire distance between the sides 2, so as to clear the pan of all ashes and cinders when the cut-off 5 is drawn 35 out. Scraper-blades 6 extend vertically and are located at the front ends of the discharge-openings 4, and are mounted in vertical guides 7, provided on the inner faces of the sides 2. These scraper-blades serve to clean the cut-off 40 and insure the complete discharge of the ashes and cinders when the said cut-off is drawn out. That end of the ash-pan facing the engineer and fireman is designated as the "front" end in contradistinction to that end 45 of the pan facing the front of the engine, and

is to be so understood in the accompanying description and the appended claim.

The cut-off 5 is a metallic plate whose edge portions 8 are reinforced or thickened, preferably by folding a portion of the plate upon itself, and this cut-off has an opening 9 to register with the front opening in the bottom of the ash-pan, so as to facilitate the discharge of the ashes and cinders. When the cut-off is pushed forward, the opening 9 thereof comes 55 over that portion of the bottom lying between the openings 4. A lever 10 is pivoted between its ends to a convenient portion of the engine and extends within convenient reach of the engineer or fireman, so as to be operated when 60 it is required to move the cut-off to discharge the ashes from the ash-pan. This lever is connected at its lower end by means of a link 11 with the cut-off.

Guides 12 are provided for the edge portions 70 of the cut-off to operate in, and are formed by strips 13, which are made fast to the sides 2, and which have their horizontal portions extending over the reinforced edge portions 8 of the cut-off and their inner edges 14 bent downwardly so as to extend over and along the inner edges of the said thickened edge portions 8, thereby preventing the lodgment of ashes and cinders upon the said reinforced edges 8 75 and the entrance of the same into the guides 12. These strips 13 are L-shaped and their vertical portions are secured to the sides 2 in any convenient manner, and these strips, in addition to forming the guides 12, serve as deflectors to shed the ashes and cinders for the 80 purposes aforesaid.

The invention is simple and can be easily operated and can be applied to any pattern of engine on the road, and in constructing the same for a special use it is obvious that various changes in the form, proportion, and the minor details of construction may be resorted to without departing from the principle or sacrificing any of the advantages of this invention.

The most ordinary way of operating the cut-off will be by means of the lever 10. However, in some instances steam, compressed air, or other media may be employed to advantage for operating the cut-off, thereby placing the 95 100

same under the control of the engineer, as a cylinder and piston of ordinary construction can be operatively connected in any of the usual ways with the cut-off, and the pipe conveying the steam or other media to the cylinder can be supplied with a throttle which can be operated by the engineer when it is required to dump or discharge the ashes.

Having thus described the invention, what is claimed as new is—

The herein-specified locomotive ash pan having a series of discharge openings in its bottom, vertically-disposed scraper blades arranged at the front ends of the said discharge openings, a cut-off operating over and upon the ash pan bottom and having a discharge opening to register with a discharge opening of the bottom, said cut-off being a flat plate

having thickened or reinforced edge portions, and L-shaped strips secured to the inner faces of the ash pan sides and having their horizontal portions extending over the upper sides of the thickened edge portions of the cut-off, and having their inner edge portions bent vertically and extending down in front of the aforesaid thickened edge portions of the cut-off, substantially as set forth for the purpose described.

In testimony that I claim the foregoing as my own I have hereto affixed my signature in the presence of two witnesses.

JOHN W. FOX.
